Patent expires January 7, 1966

3 Claims. (Cl. 192—150)

1

The present invention relates to an improved mechanism for electrically operating a member to be moved in two directions, particularly for opening and closing doors, windows and the like.

The object of the invention is to provide an improved operating means of the kind referred to, which is simple and robust of construction and which is adapted to be engaged and disengaged entirely automatically, independent of any element of the mechanism or of the object to be moved, not only as a result of an excessive resistance occurring against the mechanical movement of such object, but also when such object is accelerated by hand with respect to the mechanical drive, the latter fact, therefore, opening the possibility—in the case of applying the apparatus for actuating doors—of opening and closing the door or doors quicker by hand than would be effected by mechanical operation.

A further object of the invention is to provide an apparatus of the kind described, in which the mechanical operation, after having been put out of action, may be reinstated at any desired moment and in any desired position of the door or the like object.

With these and other objects in view the present invention consists in that the force for actuating the door, window or other object is provided by a reversible electric motor of which the torque is transmitted to the operating mechanism through a disengageable clutch which is engaged by the initial movement of the motor when starting up and is disengaged when the element during its movement meets a resistance exceeding a predetermined maximum value.

Further objects and advantages of my invention and the manner in which the same is to be performed will be apparent from the following description in which the invention is further explained with reference to the accompanying drawings, particularly as applied for opening and closing doors.

The drawings show more or less diagrammatically an embodiment of an apparatus according to the invention, in which:

Fig. 1 shows a front elevational view of the apparatus, partly in section;

Fig. 2 shows a longitudinal sectional view in a plane at right angles to the plane of Fig. 1.

Fig. 3 shows a horizontal cross-sectional view.

Fig. 4 is an enlarged view showing the locking means and spring pawl.

The apparatus consists of a casing 1 secured to the door frame adjacent the hinged side of the door and containing a vertically disposed

2

shaft 2 which through the medium of an elastic coupling 3 is adapted to be driven by a reversible electric motor (not shown), controlled for rotation in either direction through a low voltage-relay circuit, by two pressure buttons provided on each floor or by corresponding control-systems in other applications of the invention.

The shaft 2 has keyed thereto a worm 4 transmitting the torque with corresponding reduction of speed through a worm gear 5 to a horizontally arranged transverse shaft 6 journalled in said casing 1 and also carrying a worm 7 meshing with a worm gear 8. This latter gear is freely rotatable about a stationary vertical shaft 9 and at its lower end is provided with a circular series of axially projecting teeth 10 of equilateral triangular shape. These teeth 10 normally engage correspondingly shaped teeth 11 of a first clutch element 13, mounted for axial displacement over an enlarged portion 12 of the shaft 9, such first clutch element having a collar 14 formed thereon and being provided with a series of teeth 15 for cooperation with correspondingly shaped teeth of a second clutch element, hereinafter to be referred to. The inner face 16 of said first clutch element 13 is provided with axially directed grooves or is formed in any other manner as a braking surface for cooperation with braking or locking elements which in the present case are in the form of spring operated balls 18, arranged within radial bores 17 of the enlarged portion 12 of the shaft 9 all for the purpose hereinafter to be set forth.

A contact strip 19 made of elastic material and resting by its own resilient force on the collar 14 of the first clutch element 13 is arranged for cooperation with a second adjustable contact element 20, conductively secured to a strip 21, such strips 19 and 21 being connected with terminals 22, 23 respectively, passing through the wall of the casing. The circuit closing and opening means thus formed is arranged in a so-called locking-circuit parallel with the actuating pressure button switch of the motor.

45. The above-mentioned second clutch element 24 is mounted for axial displacement on a shaft 25, journalled in a chamber of the enlarged portion 12 of the shaft 9, such first-mentioned shaft passing through a stuffing box 26 and arranged to operate an arm or rod (not shown) for opening and closing the door and for operating the bolt of the lock.

The clutch element 24 is acted upon by a returning pressure spring 27, while between the two clutch elements 13, 24 a second pressure spring

28 is arranged in a chamber of the clutch element 24, such spring, however being weaker than the returning spring 27.

The operation of the apparatus is as follows:

With the door closed or opened, the elements of the apparatus are in the position shown in Fig. 2, i. e. the clutch 13, 24 is disengaged and the teeth 10, 11 are engaged throughout the entire height of the teeth. To open the door the corresponding pressure button on one of the floors is pressed, the electric motor through the said relay circuit is started for driving through the shaft 2, worm gear 5, shaft 6 and worm 7, the worm gear 8 with correspondingly reduced speed in the required direction of rotation. The clutch element 13 coupled with the worm gear 8 through the teeth 10, 11 in this position of the clutch is initially locked by the balls 18 against rotation, so that the teeth 10 by wedge-action, effect an axial displacement of the clutch element 13 against the resistance of the spring 28, thereby causing such first clutch element to be engaged with said second clutch element 24. At this instant the braking surface 16 on account of the axial displacement of the clutch element 13, is disengaged from the balls 18, so that said clutch element 13 is carried along by the still partially engaged teeth 10, 11 thereby driving said second clutch element.

With this first clutch element 13 also moves the resilient contact strip 19 resting on the collar 14, to engage the contact element 20, so that the motor-circuit is closed through the parallel locking-circuit allowing the respective pressure button to be released.

The rotation of the shaft 25 first causes the bolt of the lock to be retracted through the medium of the said operating mechanism and thereupon the door is swung open. When the door in its completely open position strikes an abutment, or when in some other way an excessive resistance is set up against the movement of the door, the shaft 25 is held or braked, causing the teeth 10, 11 to operate again as co-operating wedge-faces for displacing the entire clutch 13, 24 against the force of the resistance spring 27 downwards until the apices of teeth 10 snap over the apices of teeth 11. The clutch 13, 24 is now moved upwards as a whole by the spring 27 until the clutch element 24 attains its highest position shown in Fig. 2, whereupon the tensioned spring 28 disengages the clutch by forcing the clutch element 13 upwards into its starting position in which the teeth 10, 11 are again engaged throughout their entire height. Simultaneously the contact 19, 20 is opened thereby breaking the motor-circuit and causing the electric motor to be stopped. It will be apparent that if desired the door may now be closed by hand as the clutch is disengaged.

For mechanically closing the door, the other pressure button is pressed, thereby starting the electric motor for rotation in the opposite direction. The engagement of the clutch and the taking over of the motor-circuit by the contacts 19, 20 is effected in the same manner as above described, so that the shaft 25 is now driven in opposite direction, thereby causing the door to be first swung to until it abuts against the rabbet of the door frame. Since the pressure on the door continues the bolt of the lock is forced back by the mechanism not shown, and the door on account of its low speed is pressed with hardly any noise into the rabbet of the door frame, thereby causing the bolt to enter the opening

in the lock plate. When the resistance against the closing movement of the door exceeds the resistance represented by the adjustable pressure spring 27, the disengagement of the clutch and the stopping of the motor is effected in the same manner as stated above, after which the door is again entirely free and may be operated by hand in the normal manner.

Disengagement of the clutch will also occur when the complete closure of the door is prevented e. g. by an obstruction between the door and the threshold. After removing the obstruction the door may be closed freely by hand.

It will be apparent that the invention is not restricted to its application for operating doors, windows and the like, but that the apparatus may be advantageously employed in all cases in which an element is to be actuated or moved in two opposite directions.

20 What I claim is:

1. A clutch mechanism, particularly for use in an apparatus for operating a body to be moved in two opposite directions, comprising a first clutch element consisting of an axially fixed part 25 adapted to be rotated in either direction and an axially movable part, the adjacent faces of said two parts having interengaging double sided wedge faces, a second clutch element adapted to be axially displaced against the action of a 30 spring force, means for holding said second part of said first clutch element against rotation relative to said first part up to the moment of its engagement with said second clutch element thereby causing said wedge faces to effect axial 35 displacement of said second part upon rotation of said first part in either direction, said wedge faces being dimensioned for producing a maximum axial displacement of said second part, greater than that necessary for engaging said 40 second part with said second clutch element, and spring means arranged between said second part and said second clutch element and dimensioned to normally hold said wedge faces in full engagement with a force less than that counter- 45 acting the axial movement of said second clutch element.

2. A clutch mechanism as claimed in claim 1, characterized in that the axially displaceable part of said first clutch element over a portion 50 of its length is provided at one of its peripheral surfaces with a braking surface for cooperation with at least one locking member arranged in a stationary element of the mechanism.

3. A clutch mechanism as claimed in claim 2, characterized in that said locking member is in the form of a ball arranged in a bore of said stationary element and a spring also arranged in said bore and operating to force said ball in frictional engagement with said braking surface.
